CLAIM

An ornamental design for a winged sunshade as shown and described.

DESCRIPTION

FIG. 1 is a front view of a winged sunshade.

FIG. 2 is a rear view of the winged sunshade.

FIG. 3 is a bottom view of the winged sunshade.

FIG. 4 is a top view of the winged sunshade.

FIG. 5 is a left-side view of the winged sunshade.

FIG. 6 is a right-side view of the winged sunshade.

FIG. 7 is a front view of a winged sunshade having a light reflective surface.

FIG. 8 is a rear view of the winged sunshade with the light reflective surface shown in FIG. 7.

FIG. 9 is a bottom view of the winged sunshade with the light reflective surface shown in FIG. 7.

FIG. 10 is a top view of the winged sunshade with the light reflective surface shown in FIG. 7.

FIG. 11 is a left-side view of the winged sunshade with the light reflective surface shown in FIG. 7; and,

FIG. 12 is a right-side view of the winged sunshade with the light reflective surface shown in FIG. 7.

The claim is directed to a sunshade canopy. The shorter dashed lines along the periphery depict stitching and form no part of the design and the longer dashed lines depict sunshade ribs, poles and handles and form no part of the design.

1 Claim, 12 Drawing Sheets
